ABRASIVE TOOL

Alfred K. Johnson, Chicago, Ill.

Application June 12, 1941, Serial No. 397,673

7 Claims. (Cl. 51—185)

The invention relates to improvements in abrasive tools especially adapted for sharpening skates or the like and has for its primary object the provision of an improved tool of the character indicated which is capable of economical production and highly efficient in use.

Other objects will appear hereinafter.

The invention consists of the combinations and arrangements of parts hereinafter described and claimed.

The invention will be best understood by reference to the accompanying drawing forming a part of this specification and in which

Fig. 1 is a side view of the tool embodying the invention;

Fig. 2 a partial vertical longitudinal section of the same;

Fig. 3 a section taken substantially on line 3—3 of Fig. 2;

Fig. 4 a view similar to Fig. 2, on a smaller scale and showing a slightly modified form of construction; and

Fig. 5 a section taken substantially on line 5—5 of Fig. 4.

The embodiment of the invention illustrated in the drawing comprises a flexible tubular abrasive member 10 preferably formed from a sheet of emery cloth or the like having its edges overlapped and adhesively secured together at 11 as shown in Fig. 3. Wedges 12 and 13 are arranged as shown to be inserted within the member 10 to stretch the same when said wedges are forced together, the wedge 13 being made longer than the wedge 12 to facilitate such a stretching action and also the removal of the wedges as will be readily understood. In this way the abrasive member 10 is stretched so taut as to be comparable to a sharpening stone. The outer edges 14 and 15 respectively of the wedges 12 and 13 are rounded as indicated and said wedges are transversely tapered so that the edge 14 is materially smaller than the edge 15 as shown in Fig. 3 thereby giving the assembly substantially the shape of a "slip stone," known to the trade as such.

By this arrangement an abrasive tool is provided which is especially adapted for sharpening or polishing the bearing edges of ice skate runners. In use the tool is held in the hand with the thumb or one finger projected beyond one rounded edge and applied to the edge of the skate runner with the projecting thumb or finger rubbing against the side of the runner to serve as a guide for such application. By making the

edges of the wedges rounded and of different sizes the tool is adapted for use on runners having different sizes or different degrees of curvature in their cutting or bearing edges. When one portion of the abrasive member becomes worn the same may be readily shifted in position on the tool by releasing the wedge members and inserting them in a slightly different relation or position as will be readily understood.

10 In this way when the sheet 10 becomes worn the same may be readily shifted so as to bring fresh abrasive over the edges of the tool and thereby avoid any distortion in shape as results where a stone is used.

15 In the modified form of construction illustrated in Figs. 4 and 5 three wedge members, instead of two are employed as indicated. Wedge members 12' and 13', corresponding to wedge members 12 and 13, except that they are slightly 20 smaller, are arranged to cooperate with a central longer wedge member 16 as shown. The operation is substantially the same as before.

25 While the preferred form of construction has been illustrated and described this is capable of variation and modification without departing from the spirit of the invention. It is therefore not desired to limit the patent to the precise details disclosed, but to include also such variations and modifications as fall within the scope 30 of the appended claims.

I claim:

1. An abrasive tool comprising a flexible tubular abrasive member; and cooperating wedges insertable therein to stretch the same.

35 2. The construction specified in claim 1 in which one of said wedges is longer than the other.

3. The construction specified in claim 1 in which the outer edges of the wedges are rounded.

40 4. The construction specified in claim 1 in which the outer edges of the wedges are rounded and one made larger than the other, and one of said wedges is longer than the other.

5. The construction specified in claim 1 in which the tool is provided with two tapered edges.

6. The construction specified in claim 1 in which the two cooperating wedges are employed for stretching the abrasive member.

50 7. The construction specified in claim 1 in which three cooperating wedges are employed for stretching the abrasive member.

ALFRED K. JOHNSON,
